UNITED STATES PATENT OFFICE.

LACHLAN E. MCKINNON, OF BUFFALO, NEW YORK.

DASH-BOARD.

SPECIFICATION forming part of Letters Patent No. 391,420, dated October 23, 1888.

Application filed March 3, 1888. Serial No. 266,077. (No model.)

To all whom it may concern:

Be it known that I, LACHLAN E. MCKINNON, a citizen of the Dominion of Canada, residing in Buffalo, in the county of Erie and State of New York, have invented new and useful Improvements in Dash-Boards, of which the following is a specification.

This invention relates to an improvement in the fastenings whereby the dash-frame is attached to the feet or supporting-irons secured to the vehicle body; and it has for its object to produce a simple and inexpensive fastening, the parts of which shall be concealed, so as to form a neat and sightly finish.

15 The invention consists of the improvements which will be hereinafter fully described, and pointed out in the claims.

In the accompanying drawings, Figure 1 is a vertical cross-section of a dash-board provided with my improved fastening. Fig. 2 is a horizontal section in line $x x$, Fig. 1. Fig. 3 is an elevation of one of the lower corners of the dash-board with a portion of the leather covering cut away. Fig. 4 is a vertical cross-section showing a modified construction of the fastening.

Like letters of reference refer to like parts in the several figures.

20 A represents the front end of the vehicle body or frame.

B is the dash-board frame. b is its leather covering, and C is one of the dash feet or irons whereby the dash-board frame is secured to the body A. The feet C may be of any desired form to suit vehicle-bodies of different styles.

25 d is a screw bolt or shank attached to the lower rail, b', of the dash-frame and projecting therefrom. The screw-shank d is preferably provided with a square or flat-sided neck, which is arranged in a correspondingly-shaped opening in the rail b', so as to be held against turning therein. Each foot C is provided at or near its front end with a nut or enlargement, e, having a screw-threaded opening, which is adapted to engage with the screw shank or bolt d.

When the bolt or shank d has been attached

30 to the dash-frame, the nut or threaded opening e of the dash-foot is engaged with the outer end of the screw-shank, and the foot C is turned upon the latter until its front end bears against the rear side of the rail b'. In this manner the head of the screw-shank d is tightly drawn into its seat, and the foot is 35 firmly clamped against said rail. The flat front end of the foot C finds a seat against the rail b' and rigidly holds the foot against lateral movement. When the foot has been attached to the shank d, it is secured to the vehicle-body 40 by bolts f in a well-known manner.

In the modified construction represented in Fig. 4 a smooth opening, g, is formed in the front end of the dash-foot C, and a loose nut, h, is arranged in the opening g, which nut engages with the screw-shank d of the dash-frame. 45 In this construction the front end of the dash-foot is arranged at right angles to the body of the dash-foot.

50 My improved fastening is very simple in construction and all its parts are hidden from view, thereby producing a plain and neat finish without any projecting or unsightly parts. It also has the great advantage of not requiring any special construction of dash-frame, as 55 it can be applied to any of the ordinary dashes heretofore manufactured.

I claim as my invention—

1. The combination, with the dash-frame provided with a projecting screw bolt or shank, 60 of a dash-foot provided in its front end with a screw-socket which engages with said screw-shank, substantially as set forth.

2. The combination, with the dash-frame provided with an opening, of a screw bolt or shank, d, arranged in said opening and held 65 against turning therein, and a dash-foot, C, provided at its front end with a screw-socket engaging with said shank, substantially as set forth.

70 Witness my hand this 23d day of February, 1888.

LACHLAN E. MCKINNON.
